UNITED STATES PATENT OFFICE.

WALDEMAR KOPS, OF NEW YORK, N. Y., ASSIGNOR TO KOPS BROS., INC., A CORPORATION OF NEW YORK.

APPAREL GARMENT.

Application filed March 26, 1926. Serial No. 97,586.

My present invention relates to an apparel garment and more particularly to a step-in garment comprising a continuous girdle and combined brassière so constructed that the parts of the brassière member are secured to the upper edges of the girdle member except at the back where preferably the parts of the brassière member are connected to each other. Furthermore, the construction is such that the girdle member is provided with yielding inserts making the upper portion thereof readily extensible when the parts of the brassière member are disconnected to permit the wearer to easily step into the garment, and which inserts when the parts of the brassière are connected are yieldable only to a limited extent determined by the connected parts of the brassière member, but assist in causing the upper portion of the girdle to properly fit the body when in position for use. The garment also preferably includes a reinforcing member in the front portion thereof to assist in shaping and supporting the abdomen of the wearer. The features and construction of the garment will be hereinafter more particularly described.

In the drawing Figure 1 is a perspective view illustrating the garment made in accordance with this invention.

Fig. 2 is a front elevation on an enlarged scale, and

Fig. 3 is a back elevation on a still larger scale.

The garment made in accordance with the present invention as illustrated in the drawing comprises a front member having a central section 10 and lateral sections 11 and 12. These sections of the front member extend from the upper to the lower edges of the garment whereby the lower portions thereof form parts of the girdle of the garment, and the upper portions thereof form parts of the brassière member of the garment, the upper portions being so shaped and connected as to adequately conform to and to assist in supporting the busts of the wearer. The sections of the front member are made of any suitable inelastic material.

The garment also includes side members each comprising an elastic girdle section and an inelastic brassière section. Thus in the right hand side member there is an elastic girdle section 13 and an inelastic brassière section 14, and similarly in the left hand side

of the garment the side member includes an elastic girdle section 15 and an inelastic brassière section 16. Completing the continuity of the girdle section there is a section 17 of a back which is preferably made of inelastic material. The back member of the garment also includes brassière sections 18 and 19 which are adapted to be connected and when connected complete the continuity of the brassière section of the garment.

The central section 10 of the front member is connected to the lateral section 11 thereof by a reinforcing tape 20 and suitable lines of stitching 21. Similarly the lateral section 12 of the front member is connected to the section 10 thereof by a reinforcing tape 22 and suitable lines of stitching 23. The opposite edge of the lateral section 11 of the front member is connected to the adjacent edges of the elastic and inelastic sections of the right hand side member by a reinforcing tape 24 and lines of stitching 25. In a similar manner the opposite edge of the lateral section 12 of the front member is connected to the adjacent edges of the elastic girdle section 15 and the inelastic brassière section 16 of the left hand side member by a reinforcing tape 26 and lines of stitching 27. The opposite or rear longitudinal edge of the sections 13 and 14 of the right hand side member are connected to the adjacent edges of the section 17 of the back member and also to the section 19 thereof by a reinforcing tape 28 and lines of stitching 29. In like manner the opposite or rear edges of the sections 15 and 16 of the left hand side member are connected to the adjacent edges of the girdle section 17 and the brassière section 18 of the back member by a reinforcing tape 30 and lines of stitching 31. In the side members the section 12 of the right hand side member is connected to the section 13 thereof by a reinforcing tape 32 and lines of stitching 33. In like manner the upper edge of the section 15 of the left hand side member is connected to the lower edge of the section 16 thereof by a reinforcing tape 34 and lines of stitching 35.

In the upper portion of the girdle section 17 of the back member I employ suitable inserts of elastic material. These are preferably triangular. As illustrated in the drawing, there are two of these inserts employed. The one at the left hand side of

- the garment is indicated at 36 and is connected along one edge to the section 15 by the reinforcing tape 30 and the lines of stitching 31. Along its opposite edge it is connected to the girdle section 17 by a reinforcing tape 37 and lines of stitching 38. The insert at the right hand side of the garment is indicated at 39. Along one edge this insert is connected to the side section 12 by 10 the reinforcing tape 28 and the lines of stitching 29. Along its opposite edge this insert is connected to the section 17 by a reinforcing tape 40 and lines of stitching 41. It will be noted that the upper edges of the 15 inserts continue and complete the continuity of the upper edge of the section 17 which is continuous with the upper edges of the sections 13 and 15 of the side members of the garment.
- 20 In suitable positions in the back section 17 I may employ suitable stays 42 and 43. It will furthermore be noted that the forward edges of the sections 18 and 19 of the back member extend sufficiently far below 25 the upper edge of the girdle of the garment as to permit these sections 18 and 19 at the lower portions thereof to overlie the upper portions of the back section 17 and to extend over the elastic inserts 36 and 39 therein.
- 30 The rear edge of the section 18 is provided with a reinforcing strip 44 to which in suitable positions there are secured eyes 45. Similarly the rearward edge of the section 19 is provided with a reinforcing strip 46 to which in correspondingly placed positions there are secured hooks 47, each hook 47 being adapted to engage one of the eyes 45 for connecting the sections 18 and 19 to one another. The lower edges of the sections 40 18 and 19 preferably taper upwardly from the lower ends thereof as indicated at 48 and 49 respectively so that as hereinbefore stated, when connected, the lower portions of the sections 18 and 19 overlie the upper 45 portion of the section 17 sufficiently far to completely cover the elastic inserts 36 and 39.
- 50 In the front of the garment I preferably provide a reinforcing member 50 which may be fitted with a suitable stay 51 and which extends between and has its opposite edges connected in the lines of stitching 21 and 23 which connect the central section 10 to the lateral sections 11 and 12 of the front member so that this reinforcing member 50 overlies and is adapted to assist in shaping and supporting the abdomen of the wearer of the garment.
- 55 Furthermore, as is customary, the garment 60 may be fitted with shoulder straps 52 and 53 of suitable elastic or other material, and also with hose supporters 54 and 55 depending from the front member, and 56 and 57 depending from the lateral lower portions of 65 the section 17 of the back member.

From the foregoing it will now be understood that the garment made in accordance with my present invention includes a continuous girdle and a brassière member having the lower edges of the brassière member 70 permanently connected to the upper edges of the girdle member at the front and side sections thereof, and with the back sections of the brassière member unconnected to the back section of the girdle and being provided with means centrally disposed for connecting these back sections of the brassière member to one another; and furthermore, that by virtue of the elastic inserts in the upper portions of the back section of the girdle member 75 the upper portions of the girdle are readily extensible to enable the wearer to easily step into the garment, and that when in position the closed back sections of the brassière member limit the extent to which 80 the elastic inserts in the back section of the girdle may be stretched but do not interfere with the functions of these elastic inserts in assisting in causing the upper portion of the girdle to conform to the body of the wearer. 85

I claim as my invention:

1. In an apparel garment, a front member of inelastic material comprising a section extending from the upper to the lower edges of the garment with the lower portion thereof forming a part of a step in girdle and the upper portion thereof a part of a brassière, a reinforcing member underlying the girdle portion of the front member for shaping and supporting the abdomen of the wearer, side members each including an elastic section of the step in girdle and an inelastic section of the brassière, a back member comprising an inelastic section of the step in girdle and inelastic sections of the brassière, and means 100 for connecting the edges of the inelastic brassière sections of the said back member.

2. In an apparel garment, a front member made of inelastic material extending from the upper to the lower edges of the garment 105 with the lower portions thereof forming a part of a step in girdle and the upper portions thereof a part of a brassière, side mem-

bers each including a girdle section of elastic material and a brassière section of inelastic material, the upper edge of each side girdle section being connected to the lower edge of each side brassière section and the forward longitudinal edge of each side member being connected to the adjacent longitudinal edge 115 of the front member, a back member comprising a girdle section and brassière sections all of inelastic material, the longitudinal edges of the back girdle section being connected to the adjacent edges of the side sections of the girdle, and the longitudinal edges of the brassière sections of the back member being connected to the adjacent edges of the side sections of the brassière member and also to a portion of the adjacent 120 125 130

- edges of the side sections of the girdle member, these edges of the back section of the brassière member extending from the upper edges of the garment to points appreciably 5 below the upper edges of the side sections of the girdle, and means for connecting the edges of the brassière sections of the back member.
3. In an apparel garment, a front member 10 made of inelastic material extending from the upper to the lower edges of the garment with the lower portions thereof forming a part of a step in girdle and the upper portions thereof a part of a brassière, side members each including a girdle section of 15 elastic material and a brassière section of inelastic material, the upper edge of each side girdle section being connected to the lower edge of each side brassière section and the 20 forward longitudinal edge of each side member being connected to the adjacent longitudinal edge of the front member, a back member comprising a girdle section and brassière sections all of inelastic material, the longitudinal edges of the back girdle section being connected to the adjacent edges 25 of the side sections of the girdle and the longitudinal edges of the brassière sections of the back member being connected to the adjacent edges of the side sections of the 30 brassière member and also to a portion of the adjacent edges of the side sections of the girdle member, these edges of the back section of the brassière member extending from the upper edges of the garment to points 35 appreciably below the upper edges of the side sections of the girdle, elastic inserts set in the upper side portions of the girdle section of the brassière member over which the lower portions of the brassière sections of 40 the back member extend, and means for connecting the edges of the brassière sections of the back member.

Signed by me this 22nd day of March, 1926.

WALDEMAR KOPS.
